UNITED STATES PATENT OFFICE.

HOWARD I. BECKER, OF SCHENECTADY, NEW YORK, ASSIGNOR TO GENERAL ELECTRIC COMPANY, A CORPORATION OF NEW YORK.

HIGH-FREQUENCY RECEIVING SYSTEM.

Application filed July 20, 1921. Serial No. 486,218.

To all whom it may concern:

Be it known that I, HOWARD I. BECKER, a citizen of the United States, residing at Schenectady, in the county of Schenectady, State of New York, have invented certain new and useful Improvements in High-Frequency Receiving Systems, of which the following is a specification.

My present invention relates to means for receiving high frequency signals, and more particularly to a system in which vacuum tube amplifiers are employed for the amplification of the high frequency signaling currents which are impressed upon the apparatus at a receiving station.

The object of my invention is to provide an efficient and simple means whereby disturbing currents of low frequency which may be set up in the amplifying system are prevented from being transmitted to the apparatus which is employed for detecting the signals that are being received.

It is well known that in the operation of vacuum tube systems for high frequency amplification disturbing currents of low frequency may be introduced into the system by reason of certain internal irregularities in the operation of the vacuum tubes. Where several vacuum tubes are employed in cascade these disturbing currents are amplified along with the high frequency currents, and if transmitted to the detecting apparatus will affect that apparatus to such an extent as to interfere with the detection of the desired signals.

In order to overcome this disadvantage I provide between the apparatus which is employed for amplifying the high frequency currents and the detecting apparatus a link circuit which is so arranged as to effectively transmit to the detecting apparatus the high frequency signaling currents and which will effectively prevent the transmission to the detecting apparatus of any low frequency disturbing currents which are set up in the amplifying apparatus either by reason of the irregularities in the operation of the apparatus, or by interaction between the desired signaling currents and other currents of a neighboring frequency which may be impressed upon the amplifying apparatus.

In carrying my invention into effect I preferably arrange the output coil of the amplifying apparatus in noninductive re-

lation to the input coil of the detecting apparatus. One form of link circuit which may be employed to advantage is made up of an inductance and capacity, the inductance being coupled to both the output coil of the amplifying apparatus and the input coil of the detecting apparatus. If this link circuit is tuned for the frequency of the high frequency signaling currents to be detected it will efficiently transfer such currents to the transmitting apparatus without transmitting to any appreciable extent any low frequency currents which may be impressed upon the output coil of the amplifying apparatus.

The novel features which I believe to be characteristic of my invention are set forth in the appended claims, the invention itself, however, both as to its organization and method of operation will best be understood by reference to the following description taken in connection with the accompanying drawing in which I have indicated diagrammatically one way in which my invention may be carried into effect.

I have indicated in the drawing the application of my invention to a radio receiving system for amplifying and detecting signaling currents received upon the antenna 1. It will of course be understood that it may equally well be employed for the reception and detection of high frequency currents received over wire line.

The signaling currents received upon the antenna 1 are impressed by means of the usual coupling transformer 2 upon the resonant input circuit 3 of the radio frequency amplifier 4 which may comprise as many stages of vacuum tube amplifiers as desired in order to secure the necessary degree of amplification. The output circuit of the amplifier 4 includes a coil 5 which is arranged in non-inductive relation to the input coil 6 of the detector 7. A link circuit between coils 5 and 6 is made up of a capacity 8 and inductance 9, which is arranged in inductive relation to both coils 5 and 6, but is loosely coupled thereto. This link circuit is tuned to the frequency of the signaling currents to be detected and may be so adjusted as to transmit such currents between coil 5 and coil 6 without transferring from one coil to the other any appreciable amount of the low frequency currents set up in coil 5. If desired an audio frequency amplifier 10

may be inserted between the detector 7 and the usual receiving telephones 11.

What I claim as new and desire to secure by Letters Patent of the United States, is:

- 5 1. The combination in a high frequency signal receiving system of means for amplifying received signaling currents, means for detecting the amplified currents and a link circuit comprising a single inductance which 10 is inductively connected between the amplifying means and the detecting means for supplying currents of signaling frequency to the detecting means and preventing the transfer to the detecting means of audio frequency currents.
- 15 2. The combination in a high frequency signal receiving system of means for amplifying received signaling currents, means for detecting the amplified currents, an output coil for amplifying means and an input coil for the detecting means, said coils being in non-inductive relation to each other, and a link circuit between said coils comprising a single inductance which is in inductive relation to both of said coils.
- 20 3. The combination in a high frequency

signal receiving system of means for amplifying received signaling currents, means for detecting the amplified currents, an output coil for the amplifying means and an input coil for the detecting means said coils being in non-inductive relation to each other, and a link circuit between said coils tuned to the signaling frequency and comprising a single inductance which is in inductive relation to both of said coils for supplying currents of signaling frequency to the detecting means and preventing the transfer to the detecting means of audio frequency currents.

4. The combination in a high frequency signal receiving system of means for amplifying received signaling currents, means for detecting the amplified currents, an output coil for the amplifying means and an input coil for the detecting means, said coils being in non-inductive relation to each other and a link circuit between said coils comprising a capacity and a single inductance which is in inductive relation to both of said coils.

In witness whereof, I have hereunto set my hand this 19th day of July, 1921.

HOWARD I. BECKER.
